UNITED STATES PATENT OFFICE.

THELESPHORE VIENS, OF MINNEAPOLIS, MINNESOTA.

BED-BOTTOM.

SPECIFICATION forming part of Letters Patent No. 756,744, dated April 5, 1904.

Application filed February 24, 1903. Serial No. 144,886. (No model.)

To all whom it may concern:

Be it known that I, THELESPHORE VIENS, of Minneapolis, county of Hennepin, and State of Minnesota, have invented certain new and useful Improvements in Bed-Bottoms, of which the following is a specification.

My invention relates to means for binding the loose ends of the interwoven wires which constitute a resilient fabric known as a "woven-wire" spring, whereby a number of the said springs may be boxed or baled, and thus shipped separate and apart from the frames, which frames may thereby be boxed or bundled, and thus shipped separate and apart from the springs, (knockdown,) thereby effecting a saving in transportation charges, and when the said separate portions have reached their destination the parts of the said frame may be put together, and the said bound springs may be affixed thereto, no machinery being necessary in the operation and no skilled workman being required in the "setting up" thereof.

To these ends my improvement consists in providing a sheet-metal clip or binder adapted to be underlaid, overlapped, and pressed upon the loose ends of the wire springs to form a binder therefor and also to serve as a means for affixing the said bound fabric to the end rails of a rectangular frame adapted to serve as a support therefor.

In the accompanying drawings, Figure 1 is a top view of a woven-wire spring adapted to the use of my clip or binder; Fig. 2, a broken section of a rectangular frame to which the said bound spring is adapted to be affixed; Fig. 3, a perspective of my sheet-metal clip or binder before it is attached; Fig. 4, a section of a woven-wire spring having one of my clips connected therewith, but not affixed thereon; Fig. 5, the same after it has been affixed thereto; Fig. 6, a section of the frame and the woven-wire spring connected by means of one of my clips. Fig. 7 is a transverse vertical section through one of the end rails and clips with the latter in position engaging the spring.

Similar letters refer to similar parts.

A is the frame, B the woven-wire spring, and C the clip or binder.

The frame A is like those commonly used save and excepting that the end rails *a* are pro-

vided with the longitudinal grooves *d*, the purpose of which will hereinafter be set forth.

The woven-wire spring B is not unlike those commonly used, forms (of itself) no part of my invention, and therefore needs no description herein.

The clip C consists of a strip of sheet metal as long and about twice as wide as the end rails *a* of the frame A. It should be fashioned of soft metal—that is to say, metal which has little or no resiliency—to the end that when folded over the loose ends of the wires which unitedly form the spring B it will remain connected therewith. Its construction and application is as follows: The sheet of metal being cut to the size hereinbefore given, I bend it longitudinally intermediate its width, thereby forming the bifold clip shown in Fig. 3, one leaf, *c*, of which is adapted to underlap and the other leaf, *c'*, of which is adapted to overlap the end portions of the woven wires constituting the spring, and thereby (when pressed together) to form a binding therefor. I then crimp or corrugate the bound ends of the spring, as shown in Fig. 5, impressing or rolling in the indentation *d*, thereby firmly affixing the clip to the spring. The springs B are now in condition to be boxed or baled for shipment, as above specified.

When the parts constituting the frames A (the side and end rails) and the springs B have reached their destination, the said rails may be connected together to form the frames by properly disposing the parts and connecting them by means of the bolts *e*, thus constructing the rectangular frame A, when the spring B may be affixed thereto, so adjusting it that the crimp or indentation *d* will rest within the grooves *b* in the end rails *a*, when the two parts may be united by driving nails *f* through the clip C and into the said end rails *a*, the interlocking of the underlying longitudinal bead *d* (the corrugation) of the clip with the longitudinal groove *b* of the end rail *a* serving (with the nails *f*) to firmly unite the parts.

Having thus described my invention and set forth its advantages, what I claim as new, and desire to secure by Letters Patent, is—

The combination with the frame embodying side and end rails, said end rails having cen-

trally-arranged longitudinal grooves on their upper faces extending throughout their length, and woven springs having their ends resting on said grooved upper faces of the end rails, of securing clips or binders for engagement with the end rails, and each comprising a sheet of soft metal bent longitudinally intermediate its width to form two leaves, one of which underlaps the end of the spring, and the other of which overlaps the end of the

spring, said leaves adapted to have a portion thereof throughout their length depressed into the groove of the end rail, and securing means passed through said leaves and into the end rail, substantially as described.

THELESPHORE VIENS.
